UNITED STATES PATENT OFFICE.

GELOS L. POTVIN, OF ALPENA, MICHIGAN.

HORSESHOE.

SPECIFICATION forming part of Letters Patent No. 226,879, dated April 27, 1880.

Application filed January 10, 1880.

To all whom it may concern:

Be it known that I, GELOS L. POTVIN, of Alpna, in the county of Alpna and State of Michigan, have invented an Improvement in 5 Horseshoes, of which the following is a specification.

The nature of this invention relates to certain new and useful improvements in the construction of horseshoes; and the invention consists in providing a horseshoe with toe and heel calks of peculiar construction, which can be removed and replaced without removing the shoe from the hoof, all as more fully hereinafter set forth.

15 Figure 1 is a perspective view. Fig. 2 is a section through the toe-calk. Fig. 3 is a similar view through one of the heel-calks.

In the accompanying drawings, which form a part of this specification, A represents a 20 horseshoe, in the heels of which are formed the slots a. The heel-calks B are provided with the dovetail studs b, which fit snugly in the slots a, and they are secured to place by screws c, which pass through them into the 25 heel of the shoe. The toe-calk D is also provided with a dovetail stud, d, which fits a correspondingly-shaped slot in the rear edge of the toe of the shoe, as shown, and it is also provided with a short clip, e, which projects in

front of the toe and prevents the calk from 30 being knocked off when secured in place by the screw c.

It will be seen that the dovetail d is cut away at the sides at its forward end to admit of its slipping into place, as otherwise the front 35 calk could not be inserted, on account of the clip e.

By this manner of attaching calks to horseshoes they may be readily removed and replaced at will without removing the shoe from 40 the foot.

What I claim as my invention is—

1. In combination with a horseshoe, a toe-calk, D, provided with a dovetail stud, d, narrowed in front, and a clip, e, and secured to 45 the shoe by means of a screw, substantially as and for the purposes set forth.

2. In combination with a horseshoe, the heel-calks B, provided with dovetail studs b, which fit in correspondingly-shaped slots a in 50 the heel of the shoe, and secured to place by screws c, substantially as and for the purposes specified.

GELOS L. POTVIN.
